SECTIONAL VENETIAN BLIND

Harold A. Adams and Willard B. Files, Bakersfield, Calif., assignors of one-fourth to Ruth P. Ingalls, Bakersfield, Calif., three-eighths to Marion T. Hallock, Delano, Calif., and said Files assignor of three-sixteenths to Ralph V. Anderson, Bakersfield, Calif.

Application April 12, 1939, Serial No. 267,360

6 Claims. (Cl. 156—17)

Our invention relates to blinds of the type known as venetian wherein slats or blades are suspended in horizontal, spaced relation, and relates in particular to a Venetian blind having a number of sections one above the other, which sections may be independently adjusted to open and closed position.

In customary Venetian blind construction the blades are suspended by pairs of vertical tapes which pass along the edges of the blades and support crossing tapes on which the blades hang. Means are provided for moving the vertical tapes in opposite vertical direction so as to rotate the blades relative to axes which extend lengthwise of the blades, this making it possible to rotate the blades from horizontal position to either upward or downward sloping position whereby passage of light and air through the blind may be controlled. In some of these Venetian blinds it is possible to manually adjust individual blades by swinging them in the suspending loops provided by the small tapes which extend from one suspending tape to the other. It is an object of our invention to provide a Venetian blind having a plurality of blind sections, each section consisting of a complement of blades or slats, each blind section having separate means for its adjustment whereby all of the blades in any blind section may be simultaneously adjusted independently of the adjustment of the other blind section or sections.

It is a further object of the invention to provide a simple and inexpensive adjusting means for a sectional Venetian blind, which adjusting means occupies substantially the same amount of space as the standard type of adjusting means employed in single section blinds.

It is a further object of the invention to provide a sectional Venetian blind wherein the several sections are suspended by separate sets of tapes, certain of these tapes being placed in overlapping relation in a novel manner.

A further object of the invention is to provide a sectional Venetian blind having several blind sections, with separate actuating means for the blind section located at the upper edge of the blind structure.

A further object of the invention is to provide a Venetian blind having several independent blind sections and independent actuating means for the blind sections disposed so as to operate on a single axis placed at a horizontal edge of the blind.

It is a further object of the invention to provide a Venetian blind having several independent blind sections and having actuating means for the blind sections supported in such relation that one actuating means operates within the other.

It is a further object of the invention to provide a Venetian blind having a lower blind sec-

tion and an upper blind section and novel means for independently supporting the lower blind section in a position below the upper blind section.

A further object of the invention is to provide a simple connector means for upper and lower tape suspensions in a Venetian blind structure of the character described.

It is a further object of the invention to provide a Venetian blind wherein the supporting tapes of an upper blind section overhang or overlie the tapes of the next lower blind section.

A further object of the invention is to provide a Venetian blind having an upper blind section wherein blades are supported by tapes and a lower blind section supported by tapes which pass under and are substantially concealed by the supporting tapes of the upper blind section.

Further objects and advantages of the invention will be brought out in the following part of the specification.

Referring to the drawings which are for illustrative purposes only:

Fig. 1 is a partly sectioned plan view of a preferred form of my invention.

Fig. 2 is a partly sectioned face view of the invention with the blind part in lowered position.

Fig. 3 is a cross-section to enlarged scale taken substantially as indicated by the line 3—3 of Fig. 2, the upper and lower blind sections being broken apart and with blades removed.

Fig. 4 is a partly sectioned end view of the blind support.

Fig. 5 is a fragmentary perspective view showing the lower portion of the upper blind section and the upper portion of the blind section.

Fig. 6 is a section to reduced scale taken as indicated by the line 6—6 of Fig. 3.

Fig. 7 is an enlarged sectional view showing the interior of the clamp 19 of Fig. 2.

As shown in Fig. 3, which pictures a small size blind made in accordance with our invention, there are upper and lower blind sections 10 and 11. The upper section 10 comprises a plurality of slats or blades 12, and the lower section comprises a plurality of slats or blades 13, the blades 12 being referred to as the upper blades, and the blades 13 being referred to as the lower blades for the reason that they are respectively in the upper and lower sections. The upper and lower sections 10 and 11 may be operated separately. For example, as shown in Fig. 2 the blades 12 may be adjusted to horizontal position, and the lower blades 13 may be adjusted to angled or closed position to shut off light through the lower section 11 while free passage of light and ventilation through the upper section 10 is maintained. With reference to one side of the blind, for example the inner side, the blades of each section 50 may be independently adjusted from downwadly

sloping position through horizontal position to upwardly sloping position.

When the blind is in lowered position as shown in Fig. 2, the upper blades 12 are supported by suspension elements including tapes 14 and 15 which are spaced apart in horizontal direction so as to extend vertically across the edges of the blades 12, and horizontal tapes 16 which extend below the respective blades 12 and have the ends thereof connected to the tapes 14 and 15, the upper connecting tape 16' being secured to the lower face of the upper blade 12' by means of small staples 17, as shown in Fig. 3. The lower ends of the tapes 14 and 15, indicated by the numerals 18 and 19, project below the upper blade 13' of the lower section 11, and black bodies of metal 20 may be employed within these end portions to serve as weights to cause the lower ends of the tapes 14 and 15 to hang straight.

The lower blades 13 are carried by suspension means including tapes 21 and 22 which pass the edges of the upper blades 12 without connection thereto, lower tapes 23 and 24, the upper ends of which are connected respectively to the lower ends of the tapes 21 and 22, and lateral tapes 25, the ends of which are connected to the tapes 23 and 24 so as to support certain of the blades 13. The lower ends of the tapes 23 and 24 are secured at 26 to the bottom blade 13b of the lower section 11, this bottom blade ordinarily being considerably thicker than the remaining blades of the blind so as to give the same added weight to assure that the blind will hang relatively taut. The entire blind is hung from a suitable support which may include a horizontal member 27, and actuating means 28 and 29 are provided respectively for the upper and lower sections 10 and 11. Such actuating means include rotary members 30 to which the upper ends of the tapes 14 and 15 are secured, and rotary members 31 to which the upper ends of the tapes 21 and 22 are secured. When the rotary members 30 are rotated, one of the tapes connected thereto will move up while the other of the tapes will move down. For example should the rotary members 30 be rotated in clockwise direction from the positions thereof indicated in Fig. 3 the tapes 14 will be lifted and the tapes 15 will be lowered, causing the upper blades 12 to tilt to an angle corresponding to the angle at which the blades 13 are shown in Fig. 3. Likewise should the rotary members 30 be rotated in anti-clockwise direction from the position thereof indicated in Fig. 3, tapes 21 will be lowered and tapes 22 will be raised so that the blades 13 will be rotated toward or through horizontal position.

The actuating means 28 comprises a hollow structure which is rotatable on the horizontal axis defined by a shaft 32, this hollow structure including a pair of the rotary members 30, a tube 33 which is disposed between the rotary members 30 and is rigidly connected thereto, and end tubes 34 and 35. As best shown in Fig. 1 the rotary members 30 include spaced plates 36 provided with hubs 37 to receive the ends of the respective tubes 33, 34 and 35, and cylindric walls 38 connecting the ends of the spaced plates 36. Accordingly, each rotary member 30 when viewed from above appears as a rectangular frame. The extremity of the tube 34 abuts a bracket 39 which projects downward from the horizontal supporting member 27, but the end tube 35 passes through and is rotatable in an opening 40 in a bracket 41 which projects downward from 75

the supporting member 27. Operating means 42 for the first actuating means 28 is shown in Fig. 4 as comprising a gear segment 43 fixed on the extremity of the tube 35, a worm screw 44 supported by a bearing 45 in position to engage the gear segment 43, a sprocket 46 mounted on the forward end of a shaft 47 which extends through the bearing 45 and carries the worm screw 44 and a ball-type chain 48 which runs over the sprocket 46, there being knobs 49 on the hanging ends of the chain 48 by which a downward pull may be applied to either side of the chain so as to rotate the sprocket as desired to cause the worm screw 44 to rotate the gear segments 43 and the actuating means 28 to which the member 43 is attached.

The shaft 32 forms a part of the second actuating means 29, projects through an opening in the bracket 39, extends through the tubes 34 and 35, and preferably enters the tube 35 so that this shaft passes through both of the spaces 50 within the rotary members 30 which form parts of the first actuating means 28. In each of the spaces 50 a rotary member 31 is fixed on the shaft 32, so that the said rotary members 31 may be rotated so as to adjust the lower blind section 11 through turning of the shaft by an operating means 51 comprising a gear segment 52 mounted on the end of the shaft 32 which projects from the bracket 39, a worm 53 supported on a shaft 54 which extends through a bearing 55 and has a sprocket 56 on its forwardly projecting end, and a chain 57 having knobs 58 on the hanging ends thereof. The rotary members 31 each include a diametrically extending web 59 with cylindric end walls 60 and radial walls 61, the upper ends of the tapes 21 and 22 being carried upward over the outer faces of the cylindric walls 60 and secured to the radial walls 61.

The tapes 21 and 22 are preferably narrower than the tapes 14 and 15, and in the preferred practice of the invention pass downward under the tapes 14 and 15. Notches 62, as clearly shown in Fig. 5, may be provided in the edges of the upper blades 12 for passage of the tapes 21 and 22. The lower ends of the tapes 21 and 22 are connected to the upper ends of the tapes 23 and 24 by means of connector plates 63 which are secured by screws 64 to the upper blade 13' of the lower blind section 11. As shown in Fig. 6 each connector plate 63 may consist of a sheet metal stamping having a transverse section 65 with a slot 66 therein and rectangular end loops 67, the opening of each loop 67 being crossed by a bar 68. The bar 68 extends parallel and close to the edge of the blade 13' and may be cut in the center so as to provide a space 69 through which a loop 70, formed on the upper end of a tape 23 or 24, may be passed so as to hang the loop 70 from the bar as shown in Figs. 3 and 5. Into the ends of the transverse member 65 slats 71 are cut so as to form fingers 72 in position to underlie the edges of the blade 13' in parallel relation to the bars 68. Loops 73 formed on the lower ends of the tapes 21 and 22 are passed over the fingers and are firmly clamped against the blade 13' when the screws 64 are tightened. Accordingly, the tapes 21 and 22 are connected to the tapes 23 and 24 through the medium of the connector plates 63. The lower ends 18 of the tapes 14 and 15 pass through the loops 67 of the connector plates 63 and slide therethrough as the tapes 14 and 15 move relative to the connector plates 63.

Lift cords 74 of customary type are provided,

these cords having their lower ends 75 secured to the bottom member 13b and being extended up through openings or slots 65' in the blades 12 and 13 to small pulleys 76 supported in the supporting member 27. These cords pass from the pulleys 76 through a channel 77 in the member 27 and are bent down over pulleys 78 near the right end of the member 27 and pass through a simple clutch device 79 so as to provide a depending loop 80 by which the lift cords 14 may be pulled so as to raise the blind. The blind may be lifted to any desired extent with the upper and lower sections 10 and 11 thereof in any of their positions of adjustment, without disturbing the adjustment of the upper and lower sections, this making it possible to adjust the blind sections to desired position and then raise and lower the blind, the sections always assuming their selected positions of adjustment when lowered or extended.

A further feature of the invention consists in the provision of means for holding the tapes 14 and 15 taut when the upper blades 12 are moved into angled position, such means consisting of resilient plates 81 providing fingers which project below the lower edges of the cylindric walls 38 of the rotary members 30, the upper ends of the tapes 14 and 15 being secured to the walls 38 by the upper portions of the plates 81 which are clamped against the upper ends of the tapes 14 and 15 by screws 82. When either cylindric wall 38 is lowered from horizontal position as shown in Fig. 3, the lower portions of the plates 81 will press inward against the upper end portions of the associated tapes 14 and 15, thereby stretching these tapes taut.

As shown in the fragmentary detail Fig. 7, the clutch means 79 comprises a plate 83 across which the cords 74 may pass and a movable clutch part 84 carried by a pivot 85 and urged in upward direction by means of a spring 86. When the cords 75 are pulled laterally in the direction of the arrow 87, the clutch member 84 will be swung into a nonclutching position, but when the cords 74 are allowed to move upward in substantially vertical position, the clutch member 84 will swing toward the wall 83 and the cords 74 will be gripped between the wall 83 and the clutch member 84.

We have herein shown a simple and practical embodiment of our invention, but it will be recognized that various parts or elements thereof may be replaced by other parts of equivalent function without departing from the spirit of the invention; therefore, it will be understood that the invention is not limited to the details of the structure herein disclosed but should be accorded full scope of the appended claims.

We claim as our invention:

1. In a Venetian blind of the character described, the combination of: an upper blind section comprising a plurality of horizontal blades; upper suspension tapes extending vertically across the edges of said blades and supporting said blades; a lower blind section below said upper blind section comprising a plurality of horizontal lower blades; lower suspension tapes extending vertically across the edges of said lower blades and supporting the same; connector plates connected to the upper ends of said suspension tapes; outer rotary means disposed at the upper edge of said upper blind section and being connected to the upper ends of said upper suspension tapes so that rotation of said rotary means

5 will move said upper suspension tapes in opposite direction; inner rotary means disposed within said outer rotary means; and suspension members extending downward from said inner rotary means under said upper suspension tapes and having the lower ends thereof connected to said connector plates so that rotation of said inner rotary means will be transmitted through said suspension member to said lower suspension tapes to move the same in opposite directions.

2. In a Venetian blind of the character described, the combination of: a first blind section comprising blades with aligned notches in the edges thereof, and first suspension means for said blades positioned so as to lie over said notches; a second blind section comprising a plurality of blades and a second suspension means for said blades of said second blind section traversing said blades of said first blind section, and 15 lying in notches under said first suspension means; and means for adjustably supporting said first and second suspension means.

20 3. For use in a sectional Venetian blind, of the character described, having a plurality of blind sections each comprising a plurality of blades, with separate suspension means for the blades of the different sections; a guide plate to be secured in a position extending across one of the blade members of a blind section, said plate having guide openings in the ends thereof to receive selected suspension means.

25 4. For use in a sectional Venetian blind, of the character described, having a plurality of blind sections each comprising a plurality of blades, with separate suspension means for the blades of the different sections; a connector plate to be secured in a position extending across one of the blade members of a blind section, said plate having means at the ends thereof for connection 30 to suspension means.

35 5. For use in a sectional Venetian blind, of the character described, having a plurality of blind sections each comprising a plurality of blades, with separate suspension means for the blades of the different sections; a connector and guide plate to be secured in a position extending across one of the blade members of a blind section, said plate having means at the ends thereof for connection 40 to selected members of said suspension means and loops providing guide openings to receive other of said suspension means.

45 6. In a sectional Venetian blind of the character described, the combination of: a horizontal bar; supports at the ends of said bar; a plurality of approximately rectangular frames having walls in crossing relation to said bar, there being openings in said walls through which said bar passes; spacer members lying along said bar, the ends of said spacer members being connected to 50 said frames so as to join the same into a structure substantially coextensive with said bar; rocker members secured to said bar within said frame; blade suspension members extending downward from the outer portions of said frame; blade suspension members extending downward from the outer portions of said rocker arm; means contiguous to one of said supports to rotate said bar on its axis; and means connected to 55 said structure which includes said frames, for rotating said structure so as to simultaneously rotate said frames independently of the rotation of said bar and the rocker arms secured thereto.

HAROLD A. ADAMS.
